UNITED STATES PATENT OFFICE.

CLEMENT C. HAWKINS, OF PORT NECHES, TEXAS, ASSIGNOR TO THE TEXAS COMPANY, OF NEW YORK, N. Y., A CORPORATION OF TEXAS.

MOLDING ASPHALT.

Application filed August 24, 1921. Serial No. 494,800.

To all whom it may concern:

Be it known that I, CLEMENT C. HAWKINS, a citizen of the United States, residing in Port Neches, county of Jefferson, 5 and State of Texas, have invented certain new and useful Improvements in Molding Asphalt, of which the following is a specification.

This invention relates to improvements in 10 molding asphalt and similar material and in preparing same for shipment and refers particularly to an improved system of preparing the harder grades of asphalt for the market.

15 In present methods of preparing asphalt for the market the asphalt is placed and shipped in barrels or other containers of various types. The primary object of my invention is to obviate the use of packages in 20 which to ship the asphalt thereby reducing the expense of marketing the product.

A further object is to provide a mold of 25 such nature that the asphalt may be prepared for shipment in molded pieces which are easy to handle and are of convenient form and size for the customer.

A still further object of the invention is 30 to provide a mold of such nature that the molded asphalt may be removed from the mold with ease and with a minimum of labor.

My invention contemplates a system in 35 which the asphalt is molded in cylindrical containers of such nature that while certain parts of the mold are permanently and rigidly secured together, certain other parts thereof are temporarily held in position and may be easily loosened to release the molded product. The mold of my invention preferably assumes the form of a cylindrical body having a bilge such as the configuration of a barrel. The bilge may be formed 40 by means of longitudinally extending members having a greater diameter in the central portions thereof than at the ends. The lower ends of the members or staves are rigidly and permanently secured together while the upper ends are temporarily held in position in such manner that when the 45 means for holding together said upper ends is released they are opened up or spread apart above the bilge and thus enable the asphalt to be removed from the mold with facility.

50 In the accompanying drawings I have il-

lustrated a preferred form of mold constructed in accordance with my invention and constituting an embodiment thereof and in which:

Figure 1 is a view in perspective showing 55 the mold in position for molding the product.

Figure 2 is a view showing the mold in open position for releasing the asphalt, the frame of the mold being partially broken 60 away to expose a portion of the molded product.

In the preferred form of apparatus illustrated the mold is substantially cylindrical in form and includes a plurality of longitudinally extending members 10 which are in the form of strips or staves of less width at the ends thereof than in the more central portions. The staves or strips are fitted edge to edge to form a circle and since the 70 ends are of less width than the other portions the result is that the cylinder formed contains a bilge, as in a barrel.

One end of the cylindrical mold contains a closure while the other end preferably remains open. Retaining means, preferably of a substantially permanent nature, is provided to rigidly hold the staves in position at the closed end of the mold. Thus the mold may be equipped with one or more 75 hoops 11 secured by nails or rivets 12. A wire 13 secured by nails 14 is shown, the wire being desirable when the mold is constructed of wood. It is to be understood that the mold may be formed of wood, metal 80 or any other suitable material.

The longitudinal strips or staves 10 at the open end of the mold are temporarily held together by suitable hoops or wires arranged in such manner that they may be 85 readily removed from the mold when desired. Thus a hoop 15 and wire 16 may be used to retain the upper end of the staves 10 in position. No nails, rivets, or other the like should be employed here, since it is sufficient to merely press the hoop or wire down over the staves 10 until they are held in firm position and it is undesirable to fasten the staves at the open end in any manner that would make it difficult to remove same 90 when it is desired to discharge the molded product.

In carrying out my invention the mold is first coated on the inside with some suitable clay wash, hydraulic cement, talc, 100

fuller's earth, or any suitable material capable of preventing the asphalt from adhering to the sides of the mold. The asphalt is drawn from the still or cooling tank or other suitable receptacle while in a sufficiently heated or molten state to flow freely into the mold. The asphalt is then allowed to remain in the mold for a period sufficient to solidify. The time required for solidifying the asphalt varies according to the grade of asphalt, weather conditions, and other various factors as will readily be understood by those skilled in the art. In general, the cooling period will run from about two to six days with probably a four day period being the preferred length of time required for most grades when cooling the product under ordinary atmospheric conditions. If desired, the molds may be placed in chilling 20 chambers to hasten the solidifying.

When the asphalt is sufficiently solid the hoop 15 and wire 16 are removed, thereby permitting the staves 10 to fly or flex apart above the bilge, as clearly shown in Figure 2, and thus enable the asphalt 17 to be readily removed or drawn from the mold.

The self-supporting body of asphalt upon being released from the mold is ready for shipment without a container and in such form that it may be conveniently handled since it may easily be rolled into places of storage or into cars for shipment. It is also in a convenient and desirable form for the customer.

Upon removal from the mold the asphalt contains a coating of cement, talc, fuller's earth, or other clay material and this coating serves to protect the asphalt from injury and to prevent the molded articles from

sticking together when they are stacked for storage or shipment.

What I claim is:—

1. A barrel shaped mold comprising a circular bottom or head, a plurality of resilient staves permanently attached at their lower ends to the circular bottom or head and flaring outwardly when released at their upper ends sufficiently to permit the ready removal of a barrel shaped self-supporting body therefrom, and removable means for temporarily holding the upper ends of the resilient staves together to close the mold ready to receive the fluid material.

2. A barrel shaped mold adapted to receive a mass of material in fluid condition and to hold it until solidified into a self-supporting body of barrel shape, comprising a circular bottom or head, a plurality of staves that are tapering from an intermediate point towards both ends, and are disposed around and in engagement with the periphery of said circular bottom or head in tight edge to edge relation, permanent means for securing the lower ends of said staves to said bottom or head, and a removable hoop or ring for temporarily holding the upper ends of said tapering staves in tight edge to edge engagement while the fluid material is received and solidifies, said staves being resilient to enable their upper ends to flex outwardly when the hoop or ring is removed to allow the solidified barrel shaped body to be readily withdrawn from the mold.

In witness whereof I have hereunto set my hand this 9th day of August 1921.

CLEMENT C. HAWKINS.
